[57] CLAIM

The ornamental design for a shelving unit, substantially
as shown and described.

DESCRIPTION

FIG. 1 is a perspective view of a shelving unit embodying my new design;

FIG. 2 is a top plan view thereof;

FIG. 3 is a front elevational view thereof, the rear being
flat and unornamented;

FIG. 4 is a side elevational view taken from the left of
FIG. 1;

FIG. 5 is a side elevational view taken from the right of
FIG. 1.
